UNITED STATES PATENT OFFICE

92,778

DESIGN FOR A GARMENT CLASP

John W. Sweeney, West Reading, Pa., assignor
to The Narrow Fabric Company, West Reading,
Pa., a corporation of Pennsylvania

Application May 16, 1934, Serial No. 51,805

Term of patent 14 years

To all whom it may concern:

Be it known that I, JOHN W. SWEENEY, a citizen
of the United States of America, residing at West
Reading, in the county of Berks and State of
Pennsylvania, have invented a new, original, and
ornamental Design for a Garment Clasp, of which
the following is a specification, reference being
had to the accompanying drawing, forming part
thereof.

Fig. 1 is an elevational view of my garment
clasp.

Fig. 2 is an elevational edge view of the clasp
shown in Fig. 1.

Fig. 3 is a front elevational view of the garment
clasp shown in Fig. 1, but with the slide element
thereof in another position.

Fig. 4 is an elevational view of the garment
clasp showing the reverse side from that shown
in Fig. 1.

I claim:

The ornamental design for a garment clasp as
shown and described.

In testimony whereof I affix my signature.

JOHN W. SWEENEY.
